UNITED STATES PATENT OFFICE.

HOWARD W. GIBBS, OF BOSTON, MASSACHUSETTS, ASSIGNOR TO WILLIAM HALL & CO., OF BOSTON, MASSACHUSETTS, A FIRM.

BRAKE-HANDLE.

SPECIFICATION forming part of Letters Patent No. 707,692, dated August 26, 1902.

Application filed June 20, 1902. Serial No. 112,546. (No model.)

To all whom it may concern:

Be it known that I, HOWARD W. GIBBS, a citizen of the United States, residing at Boston, in the county of Suffolk and State of Massachusetts, have invented certain Improvements in Brake-Handles, of which the following is a specification.

My invention has for its object to simplify and improve the construction of ratchet 10 brake-handles for street and other cars and to dispense with the springs, pins, and screws commonly employed in devices of this character.

To this end my invention consists in a brake- 15 handle having a chamber at its inner end provided with vertical ratchet-teeth and adapted to receive and embrace the upper end of the brake-staff, which is provided within said chamber with a transverse slot extending 20 diametrically therethrough, in which is fitted a horizontally-sliding pawl, the ends of which are adapted on the backward movement of the handle to be alternately brought into contact with the inclined faces of the 25 ratchet-teeth, causing the opposite end of the pawl to be positively forced outward into a position to insure its engagement with the next ratchet-tooth in advance of the same to 30 unyieldingly hold the handle in locking engagement with the brake-staff when moved in the required direction to set the brakes.

In the accompanying drawings, Figure 1 is a sectional elevation of the upper portion of a brake-staff and its handle constructed in 35 accordance with my invention. Fig. 2 is a horizontal section on the line 2-2 of Fig. 1. Fig. 3 is a side elevation of the vertically-divided nut which closes the open end of the handle-chamber and holds together the handle and brake-staff. Fig. 4 is a perspective view of the sliding pawl, with the upper end of the brake-staff shown in dotted lines.

In the said drawings, A represents a car-brake handle, preferably composed of brass 45 and of the usual approved shape. Within the inner end or hub of this handle is formed a cylindrical chamber a, which is provided with a bushing b, of hardened steel, secured thereto by means of lugs or projections 10, 50 fitting corresponding recesses 12 in the handle, or by casting it therein, or in any other

approved manner, the inner wall of said bushing being provided with vertical ratchet-teeth c, as shown in Figs. 1 and 2. Within this bushing is fitted to revolve therein the 55 upper enlarged end 14 of the brake-staff C, immediately beneath which said brake-staff is embraced by a nut D, which is screwed into the open end of the chamber a beneath the shoulder 15 and serves to close said 60 chamber against the entrance of dust and hold the handle in place upon the brake-staff. The upper end 16 of the brake-staff above the enlarged portion 14 rotates in an opening 17 at the upper end of the bushing, which forms 65 a bearing therefor. The nut D is preferably divided vertically into two equal portions, as shown in Figs. 1 and 3, one portion being provided with a dowel-pin 18, fitting a hole 19 in the other, so that when the nut is un- 70 screwed it can be readily removed without necessitating the disconnecting of the brake-staff when repairs are required. The enlarged portion 14 of the brake-staff C is provided directly above the nut D with a trans- 75 verse slot d, extending diametrically therethrough, in which is fitted to slide horizontally therein a flat pawl e, the ends of which are beveled or rounded on opposite sides, as shown in Figs. 2 and 4, to adapt them to slide 80 over the inclined faces of the ratchet-teeth c as they are alternately brought into contact therewith on the backward movement of the brake-handle, the sliding pawl being of such length that when either end is caused to pass 85 over the inclined face of a ratchet-tooth its opposite end will be positively forced outward from the brake-staff into a position to insure its engagement with the first ratchet-tooth in advance of the same, thus instantly bringing 90 the handle into locking engagement with the brake-staff when moved in the proper direction to set the brakes. On the reverse or backward movement of the handle the opposite ends of the pawl will alternately pass 95 over the ratchet-teeth c, causing said pawl to slide horizontally within its slot alternately in opposite directions, so that one end or the other will always be in a position to catch the first ratchet-tooth in advance of the same 100 when the direction of the movement of the handle is reversed, all liability of slipping or

failure of the handle to be brought at once into locking engagement with the brake-staff being thereby absolutely avoided.

The above-described device by reason of the absence of all springs, pins, or screws possesses the advantages of simplicity, durability, and freedom from liability to get out of order.

What I claim as my invention, and desire to secure by Letters Patent, is—

1. A brake-operating device comprising a handle having a cylindrical chamber at its inner end provided with vertical ratchet-teeth, a brake-staff having its upper end inclosed within said chamber and provided therein with a transverse slot extending diametrically therethrough, and a horizontally-sliding pawl fitted in said slot and adapted to be moved in opposite directions by the alternate contact of its opposite ends with the inclined faces of said ratchet-teeth, whereby one or the other of the ends of said pawl will be always projected into a position to engage the ratchet-tooth next in advance of the same when the handle is moved in a direction to set the brakes.

2. In a brake-handle, the combination of a handle having a cylindrical chamber at its inner end, the inner wall of which is provided with vertical ratchet-teeth, a brake-staff having its upper end inclosed within said chamber and provided therein with a transverse slot extending diametrically therethrough, and a horizontally-sliding pawl fitted within said slot and having its ends beveled on opposite sides, said ends being adapted to be alternately brought into contact with the inclined faces of said ratchet-teeth on the backward movement of the brake-handle, whereby when said handle is moved in a direction to set the brakes, one end or the other of said pawl will be projected laterally into

a position to engage the first ratchet-tooth in advance of the same to bring the handle into locking engagement with the brake-staff, and means for holding together the said handle and brake-staff.

3. The combination of a brake-handle having a cylindrical chamber at its inner end and provided with ratchet-teeth, a brake-staff having its upper end inclosed within said chamber and provided therein with a transverse slot extending diametrically therethrough, a horizontally-sliding pawl fitted in said slot and adapted to be moved in opposite directions by the alternate contact of its opposite ends with the inclined faces of the ratchet-teeth on the inside of said chamber, and a vertically-divided nut embracing the brake-staff and screwed into the open end of the chamber in the handle to hold together said handle and brake-staff.

4. The combination of a handle having a cylindrical chamber at its inner end, a hard-metal bushing within the same provided with vertical ratchet-teeth, a brake-staff having at its upper end a portion of increased diameter inclosed within said chamber and provided with a transverse slot extending diametrically therethrough, a horizontally-sliding pawl fitted in said slot and adapted to be moved in opposite directions by the alternate contact of its opposite ends with the inclined faces of the ratchet-teeth, and a nut embracing the brake-staff beneath said enlarged portion and screwed into the open end of the chamber in the handle to hold together said handle and brake-staff.

Witness my hand this 16th day of June, A. D. 1902.

HOWARD W. GIBBS.

In presence of—

P. E. TESCHEMACHER,
M. B. FAXON.
